US0D1047593S

(12) **United States Design Patent** (10) **Patent No.:** **US D1,047,593 S**
(45) **Date of Patent:** ** *Oct. 22, 2024

(54) **BEVERAGE CONTAINER**

(71) Applicant: **Ozean International Inc**, San Marino, CA (US)

(72) Inventor: **Zhenming Ni**, San Marino, CA (US)

(*) Notice: This patent is subject to a terminal disclaimer.

(**) Term: **15 Years**

(21) Appl. No.: **29/816,318**

(22) Filed: **Nov. 20, 2021**

(30) **Foreign Application Priority Data**

May 21, 2021 (CN) 202130306201.5

(51) **LOC (14) Cl.** **07-01**

(52) **U.S. Cl.**
USPC **D7/509**

CLAIM

The ornamental design for a beverage container, as shown and described.

DESCRIPTION

FIG. 1 is a perspective view of a beverage container showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof; and,

FIG. 9 is a reduced exploded view thereof.

The broken lines depict portions of the beverage container that form no part of the claimed design.
